(57) **CLAIM**

The ornamental design for a cabinet with two doors movable in front of one another, as shown and described.

DESCRIPTION

FIG. 1 is a front elevation view of the cabinet with the doors thereof shown in a closed condition;

FIG. 2 is a side perspective view of the cabinet with a door thereof shown in a partly open condition;

FIG. 3 is a partial perspective view of a top portion of the cabinet at the circled area of FIG. 2 but as seen from the front, top and left sides of the cabinet, showing the detail of a prismatic front edge of a central upright panel of the cabinet;

FIG. 4 is a partial perspective view of a bottom portion of the cabinet at the circled area of FIG. 2 showing the detail of a front edge of a central upright panel of the cabinet and connecting a door to the cabinet;

FIG. 5 is a left side view of the cabinet;

FIG. 6 is a right side view of the cabinet;

FIG. 7 is a top view of the cabinet;

FIG. 8 is a bottom view of the cabinet; and,

FIG. 9 is a perspective view of the cabinet from the left side with a left side door in a fully open position.
